LAMP POST

Clyd R. Phillips, Coshocton, Ohio

Application May 18, 1950, Serial No. 10,026

Term of patent 14 years

(Cl. D48—31)

To all whom it may concern:

Be it known that I, Clyd R. Phillips, a citizen of the United States, residing at Coshocton, county of Coshocton, and State of Ohio, having invented a new, original, and ornamental Design for a Lamp Post, of which the following is a specification, reference being had to the accompanying drawings, forming a part hereof.

Fig. 1 is a side elevation of a lamp post, showing my new design;

Fig. 2 is a cross-sectional view of the top portion taken on the lines 2—2 of Fig. 1;

Fig. 3 is a cross-sectional view of the top portion taken on the lines 3—3 of Fig. 1;

Fig. 4 is a cross-sectional view of the upper portion taken on the lines 4—4 of Fig. 1;

Fig. 5 is a cross-sectional view of the lower portion taken on the lines 5—5 of Fig. 1; and

Fig. 6 is a cross-sectional view of the base portion taken on the lines 6—6 of Fig. 1.

I claim:

The ornamental design for a lamp post, as shown.

CLYD R. PHILLIPS.
